NECKTIE

Lucilla de V. Whitman, New York, N. Y.

Application January 8, 1953, Serial No. 23,080

Term of patent 14 years

(Cl. D3—16)

To all whom it may concern:

Be it known that I, Lucilla de Vescovi Whitman, a citizen of the United States, residing in the city, county, and State of New York, have invented a new, original, and ornamental Design for a Necktie, of which the following is a specification, reference being had to the accompanying drawing, which forms a part thereof, in which:

Fig. 1 is a front view of a necktie showing my new design as it appears in tied position and with the flaps partially opened; portions of a collar being shown in broken lines for illustrative purposes only;

Fig. 2 is a perspective view thereof as it appears in untied position and with the flaps fully opened; and,

Fig. 3 is another front view of the necktie shown in Fig. 1 as it appears with the flaps in closed position; portions of a collar again being shown in broken lines for illustrative purposes only.

This application is a continuation-in-part of my co-pending application, Serial No. D. 17,736, filed December 14, 1951, now abandoned.

I claim:

The ornamental design for a necktie, as shown and described.

LUCILLA DE V. WHITMAN.
